TRANSLATING APPARATUS FOR ELECTRIC SIGNAL PULSE COMBINATIONS

Otto Moser, Berne, Switzerland

Application December 7, 1951, Serial No. 260,522
In Switzerland December 9, 1950

10 Claims. (Cl. 178—33)

1

My invention relates to signal-pulse or code-translating apparatus such as used, for instance, with teletypewriters, printing telegraph receivers and the like electromechanical devices, for translating the incoming pulse combinations into corresponding selective control actions that effect a corresponding selective operation of type wheels, type levers, or other mechanisms. More particularly, the invention relates to translating apparatus of the just-mentioned kind in which an electromagnet, responsive to the individual pulses, has a number of separately movable armature members corresponding to the number of the combination or code units.

It is an object of my invention to improve such translating apparatus toward better reliability and uniformity of operation than heretofore attained. More specifically, the invention aims at having the control operations for each pulse combination or code character performed in a mechanically constrained manner and independently of the control operation for the other characters. It is also an object of my invention to secure a constrained and individually controlled performance without danger of bouncing.

These and other objects and advantages of the invention will be apparent from the following.

In accordance with my invention I assign to each armature member a power-driven control member for imparting a constrained motion to the armature member, and I link the control member through the armature with one of a group of displaceable selector bars so that the adjustment of the totality of selector bars determines the selection and actuation of the one type carrier or other mechanism that corresponds to the pulse combination received. These and other features of the invention will be apparent from the following description in conjunction with the drawings showing an example of translating apparatus according to the invention suitable for teletypewriters operating with a five-unit code. In the drawings:

Fig. 1 shows a schematic and perspective view of the essential mechanisms of the apparatus;

Fig. 2 shows a schematic straight-line circuit diagram of the same apparatus in conjunction with structural features of the apparatus which in this figure are diagrammatically represented without regard to their actual mechanical correlation;

Fig. 3 shows a plan view of one of the control

discs of the apparatus serving for the constrained control of the armature movement;

Fig. 4 shows a plan view of a control disc of the same apparatus serving for the control of the typing operation; and

Fig. 5 is a schematic diagram of one of two similar start-stop drive motors of the apparatus.

The translating apparatus according to Fig. 1 has a signal-responsive receiving magnet 10 with five double-armed armatures 11a to 11e individually rotatable on an armature shaft 12. The armatures are attracted by the magnet 10 as long as the transmitting circuit of the remote transmitter (not illustrated) is energized. Secured to the armature shaft 12 is a three-armed start control lever 13 whose arm 13a is also attracted by the receiving magnet 10 when the transmitter circuit is energized. A second arm 13b of lever 13 acts upon a two-position snap-action switch 14 for controlling the energization of a receiver motor 15. The third arm 13c of lever 13 carries a pin 131 which drops into a gap 16a of a grooved holding cam disc 16 when the receiving magnet 10 is not excited, i. e. when the arm 13a is dropped off under the bias of its biasing spring (not illustrated). When arm 13a drops off, the arm 13b actuates the switch 14 whereby the motor 15 is switched in and starts operating (see Fig. 2).

Motor 15 drives a shaft 18 through a reduction gear 17 (Fig. 1), the rotation being in the direction indicated by an arrow. The shaft 18 carries the above-mentioned holding disc 16 and also a stop control disc 19 with a cam 19a. Loosely seated on shaft 18 is a braking disc 20 with a peripheral notch 20a. Disc 19 has a lug 19b (see Fig. 2), and the loosely seated disc 20 has a pin 20b (see Fig. 2). In the rest condition of the apparatus shown in Fig. 1, the angular position of the discs 19 and 20 relative to each other is such that lug 19b is somewhat spaced from pin 20b. Consequently, the lug abuts against the pin after a predetermined amount of rotation of disc 19 and then entrains the disc 20.

Cam 19a of disc 19 is engageable with a break contact $k1$. Disc 20 is engageable with a break contact $v1$ (Figs. 1 and 2). Firmly mounted on shaft 18 are five control discs 21a to 21e, one for each of the respective five armature members. For clarity of illustration, only one of these control discs, namely disc 21a, is shown in Fig. 1. The control discs 21a to 21e have grooves 211 to 215 to cooperate with pins 111 to 115 (Figs. 1 and 3) of the respective armatures 11a to 11e. Respective springs 221 connected with the arma-

ture arms 22a to 22e serve to bias the arms toward the curve discs 21a to 21e when the receiving magnet 10 is not excited. Depending upon the position of the curve discs and upon the excitation of the receiving magnet in accordance with the particular pulse combination being received, a definite number of armature pins drop into the groove of the correlated respective control discs. The entrance openings 23a to 23e of the grooves in the respective curve discs 21a to 21e (Fig. 3) are angularly displaced to each other by one sixth of the periphery so that the entrance opening 23a of the first curve disc 21a performs one sixth of a full revolution relative to pin 111 before the pin can drop through this opening into the groove of control disc 21a. After another one sixth revolution of shaft 18, the entrance opening of curve disc 21b registers with pin 112 of the second armature arm 11b, and so forth.

Shaft 18 also carries a cam disc 23 whose cam projection 23a is engageable with a switch 24. This switch is temporarily actuated by the cam 23a shortly before the completion of a full revolution of shaft 18.

Five receiving bars 29a to 29e are movable in the direction of the arrow 37 in opposition to the force of respective biasing springs 30a of which only one is illustrated. Five angular levers 31a to 31e cooperate with the respective bars 29a to 29e and are linked with respective selector bars 32a to 32e. Each selector bar has a series of notches 33. Disposed above the selector bars are selector levers 34 which are linked with the type carrying arms 36 through a linkage comprising a lever 35 pivoted on a stationary shaft 35a. For clarity of illustration, only one of these selector levers and only the one pertaining group of type control means are shown on the drawing.

Each selector lever 34 is correlated to a print control disc 38 mounted on a drive shaft 40 and serving for controlling the movement of the type lever. To this end, each selector lever 34 has a pin 34a engageable with the pertaining print control disc. In the rest position of the control disc 38, all pins 34a touch the respective control discs 38 at the point 38a indicated in Fig. 4 so that the selector levers 34 do not yet touch the respective selector bars 32a to 32e. However, when during revolutions of the print control discs 38 the pins 34a reach the position 38b, the pin 34a of the one selector lever 34 fitting into the then adjusted combination of the notches 33 will drop into the recess 38b of the one pertaining print control disc. Only one selector lever 34 can drop into the notches of the selector bars at a time. The remaining selector levers 34 then rest upon the top of the selector bars so that the pertaining pins 34a cannot come into engagement with the corresponding print control discs. During the further revolution of shaft 40, the pin 34a of the then dropped-in selector lever 34 is caught by a nose 38c of the print control disc and then guided by a cam edge 38d to the original position 38a. This constrained movement of the pin 34a controls the typing operation by moving the type lever 38 about its pivot pin 38a.

As is apparent from the shape of the cam edge 38d (Fig. 4), the selector levers 34 are lifted somewhat prior to the completion of a full revolution of the shaft 40, this lifting movement being sufficient to make the selector bars 32a to 32e freely displaceable. The applicable maximum number of type levers corresponds to the number of possible pulse combinations of the particular pulse code

used. For the five-unit code therefore the maximum number of type levers is 32.

The drive shaft 40 is driven from a motor 25 through a reduction gear 26 in the direction of the arrow 40a. The control of motor 25 is effected by cam discs 41, 42, 43 mounted on the drive shaft 40. Disc 41 is firmly secured to shaft 40 and has a notch or recess 41a coacting with a make contact h. The braking disc 42 with a recess 42b is loosely seated on shaft 40 and is engageable with a make contact v2. Disc 42 has a pin 42a to cooperate with a lug 43b of disc 43. Disc 43 is firmly joined with shaft 40 and has a cam 43a to cooperate with a break contact k2. In the rest position of the apparatus, lug 43b is spaced from pin 42a so that shaft 40 and disc 43 must pass through a given angle of revolution before the lug 43 abuts against pin 42a and entrains the loosely seated disc 42.

While the drive motors 15 and 25 may be of any suitable and known type, I prefer using direct-current motors of the stepping type with self-controlled interrupter contacts as schematically shown in Fig. 5 with reference to motor 15. Such a motor has two stator coils or pairs of stator coils 15a, 15b whose fields have perpendicular respective axes and act upon a rotor 15e with salient poles. The rotor shaft carries a cam 15f acting upon two contacts m15I and m15II. The control circuit for this motor as well as that for the similar motor 25 is apparent from Fig. 2. The stator windings 15a and 15b are energized alternately and in pairs through the self-controlled contacts m15I and m15II. The field magnets 25a and 25b are similarly excited by the pertaining self-controlled contacts m25I and m25II. Such motors are especially suitable for the purpose of the invention because they can momentarily be stopped in a simple manner by magnetic action as will be explained in a later place. The motor circuits are preferably equipped with spark reducing circuit elements 15c, 25c. The motor circuits are energized from current supply mains 49, for instance, from a 60 volt direct-current line.

The operation of the apparatus is as follows: The apparatus, operating with a five-unit code, has its total period of time for the reception of an individual pulse combination subdivided into six preferably equal intervals or steps, namely a starting step and five steps for the respective units of the pulse combination to be responded to. When the transmitter issues the starting step in the form of a pause, i. e. when the transmitting circuit is interrupted, the receiving magnet 10 becomes deenergized and the armatures 11a to 11e as well as the lever 13a drop off. As a result, pin 131 of lever arm 13c drops into groove 16a of control cam 16 so that lever arm 13b actuates switch 14. Motor 15 now starts revolving the control shaft 18 with the pertaining discs 16, 19, 21a to 21e and 23. Subsequent to this starting operation, the pulse combination is received from the transmitter. Assume, for instance, that this pulse combination is composed of one pause and four current steps. In this case, the receiving magnet 10 remains unexcited for another one sixth of the receiving period. Now the feeler pin 111 of the armature arm 22a follows the bias of the spring 221 and drops into groove 211 of curve disc 21a. Due to the particular shape of the curve groove 21a, the armature member 22a is forced against the slide bar 29a and displaces it in the direction of the arrow 27. The bar 29a has two slanted edges riding on respective stationary pins so that the just mentioned displacement causes

the bar to shift perpendicularly to the displacement direction in opposition to spring 30a. As a result, the annular lever 31a is rotated counterclockwise about the shaft 31 so that lever arm 311 displaces the selector bar 32a a given amount in the direction of the arrow 32. The four next following pulses of the pulse combination, as assumed, are current pulses (positive pulses) which cause the receiving magnet 10 to be excited and to exert attracting force upon the armatures 11a to 11e. The armature 11a cannot be moved by this force because it is then being subjected to the predetermined movement enforced by the curve disc 21a. Consequently, the slide bars 29b to 29e are not influenced by the armature arms 22b to 22e and the selector bars 32b to 32e remain in their positions of rest.

The type lever 36 is now actuated as follows. Shortly before completion of one full revolution of shaft 18 and, hence, after completion of the adjustment of the selector bars 32a to 32e, the drive motor 25 is energized as explained in the foregoing so that the drive shaft 40 rotates in the direction of the arrow 40a. At the start of the shaft revolution, the pins 34a of each selector lever 34 abuts against the corresponding print control cam 38 at the point 38a. After a given amount of revolution of cam shaft 40, each pin 34a is in registry with the recess 38b, of the cam disc 38. However, the recess 38b can only be entered by the one pin whose selector lever 34 registers with all selector bar notches 33 that are then in alignment with one another. Consequently, only the one type carrying lever 36 is actuated whose type character corresponds to the received pulse combination.

The cam discs 16, 19 and 20 on control shaft 18 and the cam discs 41, 42 and 43 on drive shaft 40 serve the purpose of always securing a single full revolution of each shaft and to immediately arrest each shaft when this revolution is completed. This control operation occurs in the following manner with respect to the drive motor 15 of control shaft 18.

Immediately after control shaft 18 starts revolving, the contact k1 is opened. This contact then remains open until cam 19a of disc 19, at the completion of a full revolution, permits the contact to close. As apparent from Fig. 2 the self-controlled contacts m15I and m15II of motor 15 are shorted during the closing periods of contact k1. Then the two pairs of electromagnets 15a, 15b are excited simultaneously with the result of momentarily arresting the motor 15 in locked-rotor condition. The disc 16 takes care of having the lever arm 13b keep the switch 14 actuated during a full revolution of the control shaft 18. The cam disc 20 serves a double purpose. After starting its revolution this disc closes the contact v1 and thus secures energization of the drive independently of the switch 14. After one full revolution of shaft 18, the cam disc 20 has the further effect of providing an always sufficient braking interval for the drive 15 through maintaining the energization of drive 15 through contact v1 a short additional period of time in which the disc 20, due to its own momentum, can return to the original starting position. This momentum is due to the fact that the shaft 18 is suddenly braked to standstill so that the disc 20, being loosely seated on shaft 18, tends to continue revolving. Only after return of disc 20 into the starting position is the contact v1 opened so that then the entire arrangement is again in the starting condition.

The start-stop control for the drive 25 of shaft 40 is similarly effected by the disc 41, 42 and 43. Disc 41 closes the contact h which, after switch 24 has started the drive 25, maintains this drive in the energized condition. The contact k2, originally kept closed by cam 43a, is opened immediately after the shaft 40 starts revolving. As a result, the shorting circuit across the self-controlled contacts m25I and m25II is interrupted even when the switch 24 is again opened. However, contact k2 is reclosed upon completion of a full revolution of shaft 40 then causing the drive 25 to be braked. The disc 42 serves to extend the braking period in order to secure a definite stopping of the drive.

After the reception of a complete pulse combination, the apparatus receives a reset signal from the transmitter in the form of a current pulse so that the translating apparatus returns to its starting condition. This is followed by a starting step in form of a pause (current interruption) which initiates translation of the pulse combination next to be received.

The described apparatus has the advantage that all control operations are performed by constrained mechanisms operating independently of one another for each character to be transmitted. Besides, the provision of control discs with curved cam grooves instead of cam projections improves the guidance and control of the various control elements because it reduces bouncing as well as wearing stresses. Due to the provision of two separate drives for the translating portion of the receiving apparatus and for the pertaining printing devices greatly increases the uniformity of operation, and also simplifies the spacial arrangement with the result of considerably facilitating the assembly and disassembly of the apparatus because of the far-going mechanical separation of the receiving and translating portion from the printing portion of the apparatus.

It will be obvious to those skilled in the art upon a study of the foregoing disclosure that apparatus according to the invention may be modified in various mechanical or electrical respects without departing from the essential features of my invention and within the scope of the claims annexed hereto.

I claim:

1. Apparatus for translating electric signal pulse combinations, particularly for teletype-writers, printing telegraphs and other electro-mechanical receiving devices, comprising mechanisms to be selectively actuated in accordance with respectively different pulse combinations received, a pulse-responsive electromagnet having a number of armature members corresponding to the number of elements of the pulse combinations, said armature members being individually movable by said magnet and having respective feeler means, a revolvable control shaft having a number of control discs for controlling the movements of said respective members, said discs having respective cam grooves with pertaining entrance openings peripherally displaced relative to each other, drive means connected with said shaft for revolving it during reception of a pulse combination so that said feeler means of selected armature members enter through the entrance opening into the groove of the respective correlated control discs depending upon the state of excitation of said magnet at the moment when each feeler means registers with the correlated entrance opening, said groove

of each disc being engageable with said feeler means of the correlated armature member to impart a reciprocating stroke to said member, a stack of individually displaceable selector bars each being linked with one of said respective armature members to be displaced by said stroke, movable control structures linked with said respective mechanisms and engageable with all said selector bars of said stack to selectively move into operative position depending upon the displacement combination of said bars, a revolvable drive shaft operative upon receipt of a signal pulse combination and having curve discs engageable with said control structures only when said individual structures are in said operative portion for then displacing said structures to actuate one of said mechanisms at a time.

2. Apparatus for translating electric signal pulse combinations, particularly for teletypewriters, printing telegraphs and the like, comprising movable printing-type carriers to be selectively actuated in accordance with respectively different pulse combinations received, a pulse-responsive electromagnet having a number of armature members corresponding to the number of elements of the pulse combinations, said members being individually movable by said magnet and having respective feeler means, a revolvable control shaft having a number of control discs for controlling the movement of said members, said control discs having respective curved grooves with pertaining entrance openings peripherally displaced relative to each other, drive means connected with said control shaft for revolving it during reception of a pulse combination so that said feeler means of selected armature members enter through the entrance openings into the groove of the respective correlated control discs depending upon the state of excitation of said magnet when each feeler means registers with the correlated entrance opening, said groove of each disc being engageable with said feeler means of the correlated armature member to impart a reciprocating working stroke to said member, a stack of individually displaceable selector bars each being linked with one of said respective armature members to be displaced by said stroke, movable control structures linked with said respective type carriers and engageable with all said selector bars of said stack to selectively move into operative position depending upon the displacement combination of said bars, a revolvable drive shaft operative upon receipt of a signal pulse combination and having curve discs engageable with said control structures only when said structures are individually in said operative position for then displacing one of said structures to actuate the pertaining one of said type carriers.

3. In apparatus according to claim 1, each of said armature members comprising a spring-biased double-armed lever having one arm adjacent to said magnet to be moved thereby, said feeler means being disposed on the other arm of said member, and mechanism means connecting said other arm with one of said respective selector bars.

4. Apparatus according to claim 1, comprising start-stop drive means releasable by said magnet, said drive means being connected with said control shaft and having at said control shaft a single full revolution for each release.

5. Apparatus according to claim 1, comprising a start-stop drive releasable by said magnet and having an electric motor and a switch for controlling said motor, said motor being connected with said control shaft, a switch control cam secured to said control shaft, and means linking said cam with said switch for causing said switch to energize said motor during one full revolution of said control shaft for each release of said drive.

6. Apparatus according to claim 1, comprising a start-stop drive releasable by said magnet and having an electric motor and a switch for controlling said motor, said motor being connected with said control shaft, a switch control cam secured to said control shaft, a lever engageable with said switch for actuating said switch and having an armature portion actuatable by said magnet for causing said switch to start energizing said motor, said lever having a portion engageable with said switch control cam during a substantially full cam revolution to keep said switch energized during one full revolution.

7. Apparatus according to claim 1, comprising a start-stop drive releasable by said magnet and having an electric motor and a switch for controlling said motor, said motor being connected with said control shaft, a switch control cam secured to said control shaft, a lever engageable with said switch for actuating said switch and having an armature portion actuatable by said magnet for causing said switch to start energizing said motor, said switch control cam having a cam groove and said lever having a cam pin engageable with said groove when said lever is actuated by said magnet, whereby said lever is held by said cam to maintain said switch closed for one full revolution of said control shaft.

8. Apparatus according to claim 1, comprising start-stop drive means releasable by said magnet and connected with said control shaft, and limit stop means controlled by said control shaft and connected with said drive for stopping it at the end of one full revolution of said control shaft.

9. Apparatus according to claim 2, comprising a drive motor connected with said drive shaft for operating said type carriers, and motor control means connected with said drive motor and operatively connected with said control shaft for energizing said drive motor shortly before completion of the revolution of said control shaft.

10. Apparatus according to claim 2, comprising a drive motor connected with said drive shaft for operating said type carriers, a control circuit connected with said drive motor and having a control switch, a cam mounted on said control shaft and engageable with said control switch for causing it to energize said drive motor near the end of the revolution of said control shaft.

OTTO MOSER.
